[57] ABSTRACT

Adjustable thread drawoff apparatus, particularly in combination with stretch twist machines, having a rotatably driven godet and an associated idler roller as drawoff means with a thread or yarn wound several times around the godet and roller pair, together with a common carrier supporting or bearing the godet and roller pair and adjustable supporting means for the pivotal movement of the common carrier on a machine frame. The idler roller is preferably mounted on the common carrier with means to adjust the inclination of its axis of rotation with reference to the godet axis of rotation. The apparatus is especially useful for providing a plurality of combination drawoff means along the face of a stretch twist machine, preferably with simultaneous adjustment of all of the godet and/or idler roller axes.

ATT'YS

ADJUSTABLE THREAD DRAWOFF APPARATUS

It is generally known that idler or separation rollers can be mounted in the vicinity of godets so that the idler roller axis is adjustably inclined with reference to the machine frame for rigidly carrying one or more godet and idler roller pairs as discharge or drawoff means. Each godet and roller pair function to supply or drawoff a thread or yarn, e.g. in connection with a twisting of the thread or yarn in otherwise well known textile twisting machines, usually referred to as "stretch-twist" or more correctly "draw-twist" machines. The thread of yarn encircles the godet and its idler roller in common and is wrapped therearound several times with the individual windings being spread apart sufficiently so as to avoid interference with each other or running over one another. This separation of the windings to avoid thread or yarn damage is essentially the result of a particular angle of inclination between the godet and its idler roller, and this angle can also be adjusted by mounting the individual godet with its axis of rotation adjustably carried on the rigid machine frame. This latter technique is much less desirable than a similar adjustment of the idler roller, since the godet must ordinarily be rotatably driven and is a much heavier and bulky roller than is the idler or separator roller.

When making an individual adjustment of the angle of inclination of the idler roller or the godet on the machine frame, there is not only a change in the spacing of the thread windings around both rollers in common, but there is also a change in the position of the entire field or span of the thread winding on the peripheral contacting surface of the godet, this winding field generally being displaced toward one end of the godet such that a considerable proportion of the godet surface remains unused. This means that one must use an oversized godet, i.e. of disproportionate axial length, in order to make certain of accommodating all types of threads or yarns being treated on the textile machine. In addition, there is a tendency to unduly cause a large amount of wear in a relatively small area or yarn contacting surface on the godet, thereby requiring a more frequent replacement of individual godets.

One object of the present invention is to overcome these previous difficulties in the functioning of the individual godet and roller pairs as drawoff means, especially where large numbers of the paired rollers are arranged in parallel relationship on the face of a common machine frame and usually with a common drive shaft to operate a complete row of godets. Another object of the invention is to achieve a more carefully adjusted spacing of the thread windings as well as a more complete utilization of the yarn or thread contacting surface of each godet, preferably such that the individual windings are spread further apart and preclude any interference with one another, above all where the final thread winding runs off of the godet and idler roller pair. It is still a further object of the invention to provide improved means of adjusting the inclination or angle of the godet axis with reference to the thread running onto the godet and roller pair, as well as providing means to adjust the inclination or angle of the idler roller axis with reference to the godet axis. Other objects and advantages of this invention will become more apparent upon consideration of the following detailed specification.

The foregoing objects are generally achieved, in accordance with the present invention, by means of an adjustable thread drawoff apparatus which comprises at least one rotatably driven godet and freely rotatable 5 idler roller as combination drawoff means for receiving a thread wound a number of times around the godet and roller pair, a common carrier supportably bearing said godet and roller pair with their axes of rotation inclined toward each other, and means to adjustably support said common carrier for pivotal movement on a machine frame.

This apparatus preferably includes means on the common carrier to adjust the angle of inclination of the idler roller axis with reference to the godet axis. Moreover, it is advantageous to further include means on the common carrier to adjust the position of the idler roller in its axial direction.

Other specific and preferred embodiments of the invention are described in greater detail in conjunction with the accompanying drawing wherein:

FIG. 1 is a partly schematic front elevational view of thread drawoff means consisting of a plurality of godet and idler roller pairs carried on an elongated common carrier member which can be pivotally attached to a rigid machine frame;

FIG. 2 is an end view taken toward the right-hand side of the pivotal common carrier or casing shown in FIG. 1;

FIG. 3 is an enlarged view of FIG. 2 while further including a portion of the machine frame in cross section and greater details of the pivotal attachment of the common carrier to the machine frame;

FIG. 4 is a cross-sectional view along the axis of the idler roller and its associated adjusting means attached to the common carrier; and

FIG. 5 is a cross-sectional view taken on line 5—5 of FIG. 4.

Referring to FIGS. 1-3 of the drawing, the housing or casing 1 is adapted to receive or have fastened thereto a number of bearing boxes or sleeves 2 which carry a corresponding plurality of godets 3 to be rotatably driven by any conventional drive means. The carrier 1 also has fastened thereto the mounting bar 4 or strip 45 which receives the freely rotatable idler rollers 5 associated with each of the individual godets, an adjusting mechanism being contained within the smaller housing 6 arranged behind the mounting bar 4 and likewise connected to the common carrier 1. The idler roller 5 is also sometimes referred to as a "deflection roller" or a "separator roller". The godet drive shaft 7 extends longitudinally through the casing 1 and is carried at either end by suitable bearing members 8 and 9 which in this instance are preferably projecting flanges rigidly fastened to the machine frame 11 by any suitable bolting means or the like. This machine frame is usually a vertical member and the flanges 8 and 9 are preferably arranged so that the drive shaft 7 is positioned approximately horizontally along the face of the textile machine. A drive belt 10 or similar coupling means is operatively connected to the drive shaft 7 at one end of the carrier 1, preferably within its own housing on the outside of the bearing member 8. This rotatable drive is transmitted within the casing 1 to the individual godets 3 by means of conventional bevel gears, for example in a manner similar to that illustrated in U.S. Pat. No. 3,069,745. Thus, all of the godets in a single series

can be rotatably driven by the common drive shaft 7 while mounted on the common carrier 1.

In order to adjust the angle α , the fixed bearing flanges 8 and 9 are provided with arcuate oblong openings 12 arranged on a common circular or arcuate path so as to receive individual mounting or fixing screws 13 which are preferably secured in a releasable locking manner by means of a conventional ring and spring arrangement (not shown), the screws being inserted into corresponding screw holes in each end of the common carrier 1. These screw holes arranged in the circular path concentric with the axis of the drive shaft 7 are adapted to receive a relatively strong supporting bolt or screw 13 which is nevertheless very easily loosened so as to permit an accurate adjustment of the common carrier 1 as it is pivoted by means of the oblong arcuate openings 12 around the axis of shaft 7. This angle α of the carrier or casing 1 also represents the angle of inclination of the godet axis with reference to the vertical path at which the thread or yarn 14 is brought onto the godet and roller pair. The most advantageous angle can be readily determined by a few preliminary experiments in order to achieve the desired spread-out effect of the thread winding, and the common carrier or casing 1 can then be fixed in position by the adjusting screws or lock bolts 13.

It is particularly desirable to run the thread or yarn onto the godet in the vicinity of the collar 15 and then, after several windings around the godet and idler, the thread is preferably withdrawn more or less near the free end of the idler roller 5, depending upon its precise angle of inclination with reference to the godet axis. The best results are achieved if the individual windings 16 are widely extended or spaced as much as possible from each other. At the same time, it is usually desirable to have at least three or more windings around the godet and roller pair, depending upon the amount of tension being exerted, the yarn being treated and other well known factors.

In most winding, drawing, stretching and twisting operations or the like, it is most convenient to provide a vertical thread path for the thread or yarn over a vertically arranged textile machine, and it is for this reason that the common carrier or casing 1 is preferably pivoted about a horizontal axis which extends transversely or at right angles to the axis of rotation of the godet and preferably also at right angles to the approximately vertical path of the thread 14. Also, it is especially advantageous to arrange a large number of commonly driven godets 3 in a horizontal row, preferably on each side of a textile machine with a common coupling of the drive shaft 7, e.g. by means of belt drives 10 while the individual godets are driven through a suitable combination of gear wheels. Any suitable drive motor can be used in a conventional manner to drive the entire apparatus and maintain a substantially uniform rotational speed of all of the godets.

Referring now to FIGS. 4 and 5, the idler roller 5 is freely turnable in the supporting and adjusting mechanism 6 as illustrated by the cross-sectional view of the particular embodiment illustrated in great detail in FIG. 4. The spindle 17 of the idler 5 extends through an enlarged opening 18 in the mounting bar 4, this opening being provided with a flexible gasket or circular dust cover 19 to protect the interior of the adjusting mechanism 6. The spindle 17 is pivotally mounted in a suitable bearing means 20 recessed or set into the rear

wall 21 of the housing of the adjusting mechanism 6. At the same time, the adjusting screw 22 together with the shaft mounted spring 23 permit the spindle 17 and its attached idler 5 to be adjusted in the axial direction, i.e. 5 inwardly or outwardly from the mounting bar 4. In this manner, the idler can be readily accommodated to different godets or to different positions of inclination of the godet axis with reference to the vertical run-on path of the thread 14. In order to adjust the inclination of 10 the idler axis to the godet axis, a yoke bearing means 24 can be adjustably positioned within the housing 21 by means of the set screw 25, and these yoke bearings 24 can be individually adjustable or may be interconnected over the entire length of the mounting bar 4 so as to permit a substantially simultaneous adjustment of all of the idler rollers so as to have the same angle of 15 inclination or angle of intersection with the axis of the corresponding godets. Thus, as shown in greater detail in FIG. 5, the bearing yoke can be a common bearing bar 26 with individual set screws provided at least at both ends of the entire series of idler rollers, preferably using a number of set screws at regular intervals along the bottom of the housing 21, for example using up to 20 one set screw for each idler roller.

When constructed in accordance with the invention, the thread drawoff apparatus or similar devices, especially in draw-twist machines, permit very rapid adjustment to the most favorable angle of inclination and 25 achieve the desired winding field or span of the individual windings around the godet and idler pair. Since the general path of the thread in the textile machine runs approximately in a vertical direction, the common carrier for the godet and idler pair is preferably adjustable about a horizontal axis directed transversely to the godet axis, thereby making it possible to execute a pivoting or swinging movement of the godet in the vertical direction of the thread path. In other words, the angle 30 between the vertical thread path and the axis of the godet can be carefully adjusted without changing the angle of inclination between the godet and its associated idler roller. In this manner, the drawoff mechanism consisting essentially of the godet and its idler roller can be easily positioned to provide the most 35 favorable angles for distributing the winding field or span over substantially the entire running surface of the godet.

In addition, by using a common carrier with a plurality of such drawoff mechanisms, i.e. godet and roller pairs, a single pivoted or swinging movement in adjusting the common carrier permits all of the godets to be 40 set at a uniform angle of inclination with reference to the corresponding thread paths, and by correspondingly adjusting each of the individual idler rollers, one can achieve a uniform and carefully regulated winding pattern as the individual threads or yarns are passed several times around each godet and idler pair and finally drawn off in an otherwise conventional manner.

Moreover, it is particularly advantageous to arrange 45 the individual idlers on the common carrier or casing in positions below and laterally to one side of the corresponding godets, because the most strongly tensioned thread or yarn then runs in closest proximity to the godet while the more weakly tensioned thread or yarn taken off from the final winding at the outermost end of the godet and roller pair is relatively far removed from the godet and therefore much less capable of

being caught or otherwise influenced by the rapidly rotating godet.

The apparatus or device of the present invention permits a quick adjustment of various angles of inclination, particularly a simultaneous adjustment of several godets on a common carrier and preferably a simultaneous adjustment of the corresponding idlers with reference to their associated godets. At the same time, a greater extension of the winding field or span so as to utilize the entire running surface of each godet, i.e. with a corresponding greater spacing between individual windings, helps to avoid any collisions or interference of one thread winding with its adjacent winding or, in the case of the most weakly tensioned thread, with the godet itself. As a consequence, the apparatus of the invention permits a considerable reduction in the breakage or abrasive damage to the threads or yarns being treated on the textile machine while being rapidly transported on the godet drawoff mechanism. While these various advantages are achieved with the particular embodiments illustrated herein, it will be recognized that minor changes or variations in individual elements can be made without departing from the spirit or scope of the present invention.

The invention is hereby claimed as follows:

1. Adjustable thread drawoff apparatus comprising at least one rotatably driven godet and freely rotatable idler roller as combination drawoff means for receiving a thread wound a number of times around the godet and roller pair, a common carrier supportably bearing said godet and roller pair with their axes of rotation inclined toward each other, and means to adjustably support said common carrier for pivotal movement on a machine frame about an axis extending approximately

at right angles to the godet axis and to the direction at which said thread is run onto said drawoff means.

2. Apparatus as claimed in claim 1 including means on said common carrier to adjust the angle of inclination of said idler roller axis with reference to the godet axis.

3. Apparatus as claimed in claim 1 wherein said common carrier is arranged as a casing around and pivotally borne on a drive shaft means for said godet, said casing being adjustably fastened at either end of its axial extension along said drive shaft means to flange members projecting outwardly from and fixed to a rigid machine frame.

4. Apparatus as claimed in claim 3 wherein said each flange member contains arcuate oblong openings in a common circular arrangement and adjusting bolt means engaging in said openings to support and fasten said casing.

5. Apparatus as claimed in claim 1 including a plurality of godet and roller pairs as combination drawoff means arranged in axially parallel alignment along one face of said common carrier.

6. Apparatus as claimed in claim 5 wherein each idler roller is positioned on said common carrier on an approximately horizontal axis below and laterally to one side of its associated godet, both the godet and roller axes being at approximately right angles to the horizontal axis of said common carrier.

7. Apparatus as claimed in claim 5 including means to simultaneously adjust the angle of inclination of each idler roller with reference to its associated godet in all of said plurality of godet and roller pairs.
